[57] CLAIM

The ornamental design for a clock, substantially as
shown and described.

DESCRIPTION

FIG. 1 is a front elevational view of a clock showing my
new design;

FIG. 2 is a right side elevational view thereof, the left
side being a mirror image thereto;

FIG. 3 is a rear elevational view thereof;

FIG. 4 is a top plan view thereof;

FIG. 5 is a bottom plan view thereof;

FIG. 6 is a front perspective view thereof in a wall-
hung position;

FIG. 7 is a right side elevational view of FIG. 6, the
broken-lines of a wall being environmental only and
forming no part of the claimed design.

FIG.1

FIG.2

FIG.5

FIG.3

FIG.4
